Epitomizing

UNITED STATES PATENT OFFICE.

CARL SCRABIC, OF URBANA, OHIO.

SOUND AMPLIFIER.

Application filed June 6, 1923. Serial No. 643,770.

To all whom it may concern:

Be it known that I, CARL SCRABIC, a citizen of the United States, residing at Urbana, in the county of Champaign and State of 5 Ohio, have invented certain new and useful Improvements in Sound Amplifiers, of which the following is a specification.

The present invention is directed to improvements in sound amplifiers for talking 10 machines and has for its object to provide a device of this character which when associated with the sound conducting throat will materially amplify the sound and influence the correct reproduction of the musical tones 15 so they will be reproduced in their full value.

A further object of the invention is to provide an improved form of amplifier so constructed that the tones reproduced are of amplified volume, and at the same time 20 devoid of harshness or mechanical sound.

With these and other objects in view, as will appear as the description proceeds, the invention consists in the novel features of construction, combinations of elements and 25 arrangements of parts, and hereinafter to be fully described and pointed out in the appended claims.

In the accompanying drawing:

Figure 1 is a longitudinal sectional view 30 through the device.

Figure 2 is a sectional view on line 2—2 of Figure 1.

Referring to the drawing 1 designates a portion of a conventional form of talking 35 machine cabinet provided with the usual throat 2, said throat being in communication with the tone arm structure (not shown). The lower end of the throat is fitted in a block 3, said block having a curved 40 sound passage 4 formed therein.

A bracket 5 is mounted in the cabinet 1, and has associated therewith a screw 6 which engages the block 3 to hold the same properly positioned within the cabinet, there being a 45 felt washer 7 carried by the screw to absorb any undue sound at this connection.

The main amplifier 8 is of bell shape and of sufficient length to have its front edge lie adjacent the front wall of the cabinet 1. 50 The amplifier further comprises a plurality, preferably three in number, of auxiliary amplifiers 10, 11 and 12, which are substantially the same length but vary in diameter so that the adjacent ends thereof will be 55 disposed in telescopic or nested annular spaced order, said auxiliary amplifiers be-

ing circular in cross section and of conical formation.

It will be apparent that the auxiliary amplifiers are so arranged as to not impede 60 the flow of sound waves through the main amplifier 8, but result in increasing the resonance of the amplifier.

In order to hold the auxiliary amplifiers and main amplifier in proper spaced relation, bridge rings 13, 14, 15 and 16 are provided, the rings 16 being located to register with the passage 4 of the block 3 and is disposed concentric with respect to the minor end of the amplifier 12, said ring being suitably secured to the flange 17 associated with the block 3. The rings 14 and 15 are each provided with annular webs 18, and resultant shoulders 19, which are engaged by the minor ends of the auxiliary amplifiers 10 70 and 11. The webs 18 are provided with passage-ways 20 and centering bridge pieces 21, the bridge pieces of ring 15 being engaged with the major end of the amplifier 11, while the major end of the amplifier 12 75 is engaged with the bridge pieces of ring 15. The ring 13 is likewise provided with passage-ways 21', and bridge pieces 22, said bridge pieces engaging the major end of the amplifier 10. 80

The rings may be secured to the inner surface of the amplifier 8 in any approved manner, as will the auxiliary amplifiers to be secured to the respective rings. It will be observed that by arranging the rings as shown 90 that resonant chambers 23, 24 and 25 are provided, the interior of which being open to the atmosphere through the respective auxiliary amplifiers.

It will be further observed that these rings 95 serve to hold the main amplifier and auxiliary amplifiers in proper spaced relation, while the bridge pieces 20 and 21' hold the adjacent ends of the auxiliary amplifiers in spaced concentric relation.

It will be of course understood that the main amplifier as well as the auxiliary amplifiers are formed from material having sound resonant characteristics.

What is claimed is:

1. An amplifier for talking machines comprising a main amplifier, auxiliary amplifiers located therein and being of hollow frusto conical formation, rings interposed between the walls of the main amplifier and the auxiliary amplifiers, said rings having sound passages and resonant bridge pieces, 110

the latter engaging the auxiliary amplifier to hold the same in spaced relation from each other and from the wall of the main amplifier.

5 2. An amplifier for talking machines comprising a main amplifier, auxiliary amplifiers located therein and being of hollow frusto conical formation, rings interposed between the walls of the main amplifier and the 10 auxiliary amplifiers, said rings having sound

passages and resonant bridge pieces, the latter engaging the auxiliary amplifier to hold the same in spaced relation from each other and from the wall of the main amplifier, said rings defining resonant chambers around 15 the auxiliary amplifiers.

In testimony whereof I affix my signature.

CARL SCRABIC.
